F. W. NURENBERG

TABLE CRUMBER

Filed June 10, 1925

INVENTOR
E. W. NURENBERG

BY *John F. Anderson*
X ATTORNEY

UNITED STATES PATENT OFFICE.

FRED W. NURENBERG, OF BROOKLYN, NEW YORK.

TABLE CRUMBER.

Application filed June 10, 1925. Serial No. 36,073.

Among the principal objects which the present invention has in view are: To provide a crumb collecting device operable by the, and as a result of the, movement of 5 the crumber across the table; to insure the rotation of the collecting brush with which the crumber is provided; and to simplify and cheapen the construction.

Drawings:

10 Figure 1 is a front view of the crumber constructed and arranged in accordance with the present invention, a portion of the crumb collecting brush being cut away to show the construction therebehind, the broken lines 15 in said figure being used for showing the dumping position of the crumb tray;

Figure 2 is a top plan view of the same on enlarged scale, showing the driving mechanism for the brush partly in section, and a 20 portion of the overhang of the crumb tray cut away;

25 Figure 3 is a sectional view, the section being taken on the line 3—3 in Figure 1, the broken lines in said figure being so disposed to indicate the inactive position of the driving wheel of the driving gear;

Figure 4 is a similar view showing the driving wheel in active position;

30 Figure 5 is a cross section, the section being taken as on the line 5—5 in Figure 2.

As seen in the drawings the crumb tray has a partly cylindrical body 10, provided with a swinging flat bottom plate 11. The bottom plate 11 is held in operative relation 35 to the body 10 and the brush 12 by a spring 13. The bottom plate 11 swings on the pivot pin 14 from the closed position shown in full lines in Figure 1 to the open position shown by dotted lines in said figure, when the han-

40 dle 15 is pressed upward. The ends of the body 10 are closed by end plates 10' extending laterally of the body in parallel relation to form a bearing for the twisted wire shaft 16 of the brush 12, and a guide for the loop 45 17 formed on the bearing plate 18 which supports the boss 19 in which the short stud shaft 20 is set. The shaft 20 supports the driving wheel 21.

As seen in Figure 2 of the drawings the 50 driving gearing for the brush 12 employs a gear pinion 22, which is mounted rigidly on the shaft 16. The shaft 16 is journaled in the journal box 23 which slides in a recess 24 in the forward edge of the outer end 55 plate 10'. The teeth of the pinion 22 mesh with the teeth of the internal gear 25 with

which the driving wheel 21 is provided. The difference in the diameters of the pinion 22 and the driving wheel 21 gives the ratio of the speed to the two wheels. 60

The bearing plate 18 swings on a pivot 26. The bearing plate 18 is held in its lower position by a spring bar 27, the free end of which rests upon the boss 19, as shown best 65 in Figure 3 of the drawings.

The result of the above described construction is that whenever the operator using the handle 28 presses the apparatus upon the table cloth for collecting crumbs thereon, he forces the wheel 21 into frictional contact therewith, the wheel 21 and the plate 18 on which it is mounted yielding upwardly, the spring 27 being flexed to permit the action. Thereafter, however, the spring 27 70 operates to exert a pressure upon the plate 18 and the wheel 21, which maintains the frictional engagement of the said wheel with the table covering. As and when the wheel 21 is rotated, the pinion 22 and the brush 12 operatively connected therewith are rotated proportionately fast, and, by reason of the location of the said pinion the direction 75 of rotation of brush is the same as the wheel 21. The brush sweeps the table covering directly in front of the front edge of the tray bottom 11, and any crumbs in the path of the tray are swept rapidly by the brush upon the said bottom and into the body 10. 80

Whenever the tray is sufficiently loaded and it is desired to get rid of the contents 90 the handle 15 is pressed upward to drop the bottom 11 to the position shown by the broken lines in Figure 1. In this position of the bottom the contents of the tray are readily disposed of. 95

Claims:

1. A table crumber comprising a tray formed with a partly cylindrical body having closed ends comprised of plates extending laterally of the body, a flat bottom plate hingedly connected to one of said end plates and extending beneath said body and beneath and between said end plates in advance of said body, a rotary brush journaled between the ends of said end plates in advance of said bottom plate, a traction wheel 100 operatively connected with said brush for rotating said brush upon movement of said traction wheel over a table cloth, a plate pivotally mounted on one of said end plates, 105 a bearing for said traction wheel formed on said pivotally mounted plate whereby 110

tive movement between said brush and traction wheel is permitted, and crumber carried means for pressing said traction wheel down upon a table cloth.

- 5 2. A table crumber comprising a tray formed with a partly cylindrical body having closed end plates extending in parallel relation laterally of the body, a flat bottom plate hingedly connected to one of said 10 end plates and extending beneath and between said end plates under and in advance of said body, a rotary brush journaled between the ends of said end plates in advance

of said hinged bottom plate, a movable plate pivotally mounted on one of said end plates, 15 a traction wheel carried by said movable plate, operative connection between said traction wheel and rotary brush, and a spring bar connected at one of its ends to the end plate carrying said movable plate, said 20 spring bar bearing at its opposite end against said movable plate for retaining said traction wheel in engagement with a surface over which the crumber is moved.
